DISPENSER FOR FOLDED PAPER NAPKINS

Frank L. Broeren, Neenah, Claude S. Cole, Menasha,
Edwin A. Filipowicz, Greenfield, and David G. Hope,
Wauwatosa, Wis., assignors to American Can Com-
pany, New York, N.Y., a corporation of New Jersey

Filed July 26, 1962, Ser. No. 71,064

Term of patent 14 years

(Cl. D52—2)

Fig. 1

Fig. 2

Fig. 3

Fig. 4

Fig. 5

Fig. 6

FIGURE 1 is a side elevational view of the dispenser for folded paper napkins, showing our new design;

FIGURE 2 is a top plan view of the dispenser;

FIGURE 3 is an end elevational view of the dispenser;

FIGURE 4 is a side elevational view of a modified form of the dispenser for folded paper napkins;

FIGURE 5 is an end elevational view of the dispenser shown in FIGURE 4;

FIGURE 6 is a top plan view of the dispenser shown in FIGURE 4.

The undisclosed side of the dispenser is the same in

appearance as in the side shown, and the undisclosed end is the same in appearance as the end shown.

We claim:

The ornamental design for a dispenser for folded paper napkins, as shown and described.
